MAGNETIC CORE STRUCTURE

Allan D. Forbes, Sharon, Pa., assignor to Westinghouse Electric Corporation, East Pittsburgh, Pa., a corporation of Pennsylvania

Application July 15, 1942, Serial No. 450,971

10 Claims. (Cl. 175—356)

My invention relates to magnetic core structures for use in electrical induction apparatus such as transformers.

In electrical induction apparatus, such as distribution or power transformers, it has been the usual practice to employ a core structure of magnetic material formed of a stack of layers of thin sheets or laminations of magnetic material such, for example, as hot-rolled silicon steel. A portion of the magnetic structure is employed as a winding leg about which the copper circuit conducting windings of the transformer are wound. In order to keep the cost of the transformers as low as possible, it is desirable that the length of the mean turn of the current carrying conductor about the winding leg be as small as practicable consistent with permissible losses and power performance of the transformer.

The smaller the cross-section of the magnetic material the greater will be the flux density necessary to develop a given electromotive force and the greater will be the exciting current flowing in the primary winding. The permissible exciting current for a given size of transformer has been a factor in limiting the permissible reduction in the cross-section of the magnetic material.

The exciting current is made up of two components or parts, namely, the magnetizing current that is necessary to force the lines of magnetic flux through the iron circuit of the core, and the iron loss current necessary to supply losses of energy in the iron core structure, such as those due to hysteresis and eddy current losses. The component of magnetizing current is controlled very largely by the permeability of the material used in the core structure, and the watts loss component of current is controlled by the iron loss characteristic of the material.

The magnetic iron or steel usually employed in transformer core structures is a high grade hot-rolled silicon steel having a value of permeability and watts loss per cubic volume of substantially constant value over a considerable departure in the direction of the sheet along which the lines of magnetizing flux pass from the direction of rolling. More expensive steels have been developed having much higher permeability and much lower losses in the direction of rolling. In such material the permeability varies considerably as the direction of the lines of magnetizing force vary from the direction of rolling of the material and is the highest in the direction of rolling. The watts loss per cubic volume or per cubic weight of the material likewise varies markedly

as the direction of magnetizing flux varies from the direction of rolling of the material and is lowest in the direction of rolling.

The permeability of the new steel in the direction of rolling is considerably higher at operating densities (say 13 to 15 kilogausses per square centimeter) than the permeability of commercial grades of hot-rolled silicon steel at the same densities. Likewise the watts loss per unit volume or unit weight at operating densities when magnetized in the direction of rolling is lower than for commercial grades of hot-rolled silicon steel at the same density.

It will be seen, therefore, that if a transformer core is formed of sheet steel having a preferred or greater permeability and a preferred or lesser watts loss per unit volume when the flow of flux is through the steel in the direction of rolling than when it is through the material in other directions and the sheets are so arranged that the lines of magnetic flux pass through the steel in the direction of rolling, a higher permeability and lower watts loss will result, permitting the use of higher flux densities than are permissible with the usual grade of silicon steel, and a reduction of the cross-section of the magnetic material otherwise required.

Magnetic cores have been built with a high grade steel having a preferred permeability and low watts loss in the direction of rolling in which stacks of laminations have been used for the winding leg and yoke portions of the core. In such cases, it has been the practice to employ yoke portions of the core having a greater width from the window to the outside of the core than the width of the leg portions and arrangements of the sheets of steel forming the core have been worked out for effecting efficient joints. These arrangements, however, are not suitable to structures in which the yoke and leg portions have the same width from the window to the outside edge of the core structure.

It is an object of the invention to provide a core structure for an electrical induction apparatus made up of stacked sheets of steel having a preferred permeability or easiest magnetization in the direction of rolling so positioned in the structure that the lines of magnetization correspond substantially to the direction of rolling of the material and in which the width of the sheets for the core yoke and leg portions of the core are the same.

It is a further object of my invention to provide a core structure of the above indicated character employing combination butt and lap joints

adjacent the corners of a rectangular core structure in which the meeting edges are cut at an angle to the direction of the sheets to effect a high permeability of the core structure as a whole and as low an iron loss as possible.

Other objects and advantages of the invention will be apparent from the following description of a preferred embodiment thereof, reference being had to the accompanying drawing, in which:

Figures 1 and 2 illustrate the manner in which magnetic flux passes through core members of different designs;

Fig. 3 illustrates an arrangement of stacked sheets in a prior art core structure in which the width of the yoke members is greater than that of the width of the leg members;

Fig. 4 illustrates an arrangement of the stacked sheets of steel in a transformer core structure organized in accordance with the invention;

Figs. 5 and 6 illustrate parts of the core structure used in the assembly shown in Fig. 3; and

Figs. 7 and 8 illustrate parts of the core structure used in the assembly illustrated in Fig. 4.

Fig. 1 illustrates a conventional arrangement of the laminations or sheet steel punchings commonly used in a core structure built from high grade hot-rolled silicon steel comprising in each layer of the core structure four punchings or sheets 1, 2, 3 and 4, arranged in the same plane, the punchings 1 and 3 being alike and the punchings 2 and 4 being alike. The several punchings are rectangular in shape, the punching 1 extending from 1a to 1a', the punching 2 extending from 2a to 2a', the punching 3 extending from 3a to 3a', and the punching 4 extending from 4a to 4a', so that one end of each of the four punchings is adjacent the side of its adjoining punching. In this form of construction, the position of the four punchings will be shifted in the adjacent layer to provide an overlap between the punchings in the adjacent layers so that the punching 1 will extend from 1b to 1b', the punching 2 from 2b to 2b', the punching 3 from 3b to 3b', and the punching 4 from 4b to 4b', the punchings in the second described layer forming the same general pattern as those in the first described layer but with the positions of the adjoining edges shifted from the full line positions 1a, 2a, 3a and 4a to the dotted line positions 1b', 2b', 3b' and 4b'.

In the structure shown in Fig. 1, the core legs 2 and 4 may be winding legs of the core structure about which the primary and secondary windings of the transformer are placed and the connecting portions 1 and 3 form the yokes connecting the winding legs to complete the magnetic circuit of the core structure. In this structure the lines of the magnetic flux pass lengthwise through the straight portions of the legs and yoke, and flow about the corners of the structure something after the fashion indicated by the arrowed lines 6, so that near the ends of the punchings the flux must pass sidewise of the members across the grain of the steel. This construction is entirely satisfactory for cores employing conventional hot-rolled steel where the permeability is not much different at right-angles to the direction of rolling from its value in the direction of rolling, but experience has shown that it is unsuited to the use of the new type steel having a much greater preferred permeability and lower watts loss when the lines of magnetic flux pass through the material in the direction of rolling than when these lines of flux pass through the material in other directions. For such new type steel, in order to make efficient use

of the properties of the material, it is necessary to employ a construction in which the lines of flux follow the direction of rolling, or easiest magnetization, at all points.

In Fig. 2 of the drawing it will be noted that the adjoining edges of the several sheets 1, 8, 9 and 10 comprising a layer of the core material are cut on a diagonal or at an angle to the direction of the sheets. In this core the flux will tend to follow the direction of easiest magnetization, as shown by the arrow lines 11, although this may not be the shortest path around the corner. By following this path of easiest magnetization or least resistance, the lines of flux avoid the necessity of passing crosswise to the direction of rolling near the ends of the sheets of each lamination.

In Fig. 3 a core structure is shown comprising stacks of sheet steel parts 14, 15, 16 and 17 arranged about a window having a length L and a width W. The leg members 15 and 17 are shown as having a width N and the yoke members 14 and 16 as having a greater width of N+n. The members 14 and 16 are alike in shape and as best shown in Fig. 5, the inner edge of the sheet has a length W corresponding to the width of the core window. The sheets 15 and 17 are also alike and as shown in Fig. 6, have a length along the inner edge indicated by L+n, which is somewhat greater than the length L of the core window. The members are so arranged in the core structure that in each layer one end of the sheets comprising the leg members extends from a point 18 at the inner angle of the window to a point 19 at the other end of the inner edge of the sheet that is offset from the inner angle of the corner of the window. The diagonal ends of the sheets at one end extend from the inner angle of the window 18 to a point 21 offset from the outer corner of the core and at the other end from the outer angle of the core 22 to the point 19 which is offset from the inner angle of the window. In adjacent layers, the members 14 and 16 are reversed end for end and the members 15 and 17 are so positioned that the adjoining edges in one layer follow the full line outline 18, 21, 22 and 19, and in the adjoining layer the dotted line outline 18', 19', 22' and 21', providing an overlap between the sheets in the adjacent layers shown by the space between the lines 18-21 and 18'-22'. The corresponding points in the two layers are given the same number but are primed in the dotted line position.

This prior art core structure works well when the core and leg members of the structure are of different widths, but, it will be appreciated that when the core and leg members are of the same width, the diagonal lines extending inwardly from the outer angle of the core and extending outwardly from the inner angle of the core would bring the adjoining edges of the sheets in adjacent layers opposite one another, eliminating the overlap and resulting in a core structure similar to that shown in Fig. 2, in which the superimposed layers are alike.

The principle illustrated with respect to Fig. 2 is made use of in the core structure shown in Fig. 4, the sheets of steel comprising the core being so arranged that the adjoining edges of the sheets in different layers extend on opposite sides of a line joining the inner corner of the window with the outer corner of the core to form an alternate butt and lap joint having a lower joint reluctance than would be the case if all layers were built as shown in Fig. 2, in which the diagonal line forming the junction between

the sheets in the several layers were superimposed upon each other.

In accordance with my invention, a core structure is provided in which the yoke and leg portions are of equal width N . The stacks of four punchings 24, 25, 26 and 27 are arranged about the core window, the sheets 24 and 26 corresponding to the sheet shown in Fig. 7, and the sheets 25 and 27 corresponding to the sheets shown in Fig. 8. The sheets 24 and 26 have a length along their inner edge of $W+x$, which is somewhat greater than the width W of the core window and the sheets 25-27 have a length along their inner edge of $L+x$, which is somewhat greater than the length L of the core window. In the full position of the sheets 24 and 26 comprising the yoke members in Fig. 4, it will be noted that the corner 31 of the sheet is positioned at the inner angle of the window and the edge of the sheet extends to an angle point 32 which is in line with the extended inner edge along the length of the window, and from that point the adjoining edges between the sheets 24 and 25 and between sheets 26 and 27 extend along the lines 32-33 in a direction parallel to a line joining the inner angle of the window with the outer angle of the core; then along the outer edge of the core to the corner 34, and then along the edge length of the core to the point 35, then parallel to the line adjoining the outer corner of the core with the inner angle of the window to the angle point 36, and from the angle point 36 to the corner of the window 31 along a line which includes the edge of the window and an extension thereof. In the adjoining layer, the members 24 and 26 will be reversed end for end so that the same outline will apply in reading the same numbers as primed, that is, the sequence 31', 32', 33', 34', 35' and 36' outlining the corresponding points in the sheets. Likewise in adjacent layers, the members 25-27 are reversed end for end so that the edges of the leg members join with the edges of the yoke members.

It will be noted, therefore, that in each layer of sheets about the window each sheet 24, 25, 26 and 27 extends along its inner edge from a corner of the window at one end to an angle point in the sheet which is at a point displaced from the angle of the window at the other end by continuing the inner edge of the sheets a distance x beyond the inner angle of the window. By reversing this pattern in adjacent layers so that the angle points 32 and 36' or 32' and 36 in adjacent layers are on opposite sides of a straight line joining the inner angle of the window with the outer angle of the core, an overlap between adjacent layers of constant width is provided. This overlap is the area shown between line 32 and 33 and line 36' and 35' or between line 32'-33' and 36-35.

It will be noted that in accordance with the structure shown in Fig. 4 comprising the invention, the benefits of the diagonal cut as described with respect to Fig. 2 are provided without the necessity of providing widening of the yoke members, as is required in the structure shown in Fig. 3. In the structure shown in Fig. 4, the yoke members have the same width N as the leg members. This results in a saving in magnetic steel which in many applications is desirable.

It will also be noted that the overlap of the sheets adjacent the corners of the core may be varied by varying the dimension x in the lengths $W+x$ and $L+x$ of the sheets of steel shown in Figs. 7 and 8 respectively, without varying the

width of the yoke member with respect to the leg member. This permits a more flexible design of the joint structure than where the overlap is dependent upon the relative widths of the yoke and leg members.

It will also be noted that the sheets comprising the core structure 4 are identical in shape and differ only in length, so that an economy is effected in that the same die construction may be used to make the same punchings and both punchings may be made from the same sheet of steel since the width required for both punchings is the same. The dies may be arranged to cut alternately a leg piece and then a yoke piece from the same strip of steel since both pieces are of the same width and the same shape at the ends. Any variations in the gauge thickness of the sheets of material is thus minimized or eliminated in the assembled core. Where it is necessary to cut the yoke pieces from a different strip of material than the leg pieces and if the two strips should be of slightly different thicknesses, it is possible that all of the yoke pieces may be thinner than the leg pieces, or vice versa, thus introducing difficulties in assembling the core and in improperly distributing the losses between the core and yoke members. These difficulties are eliminated in the construction shown in Fig. 4.

It will be apparent to those skilled in the art that modifications in the detailed arrangements of the parts of the structure may be made within the spirit of my invention, and I do not wish to be limited otherwise than by the scope of the appended claims.

I claim as my invention:

1. In an electrical apparatus, a substantially rectangular magnetic core structure built up from layers of sheets of magnetic material formed of steel having preferred greater permeability and lower watts loss in the direction of rolling than in other directions and so positioned in the structure that the direction of magnetization is substantially coincident with the direction of rolling, each layer comprising a plurality of sheets having adjoining edges adjacent the corners of the core structure and arranged about a substantially rectangular window, the sheets on all sides of the window being of the same width, the junctions of all adjoining edges at the outer corners of the magnetic core extending along lines formed by continuing the inner edge of one of the adjoining sheets at each corner of the window in a straight line in the direction of rolling slightly past the corner of the window to an angle point of the sheet and from that angle point in a continuous straight line at an angle oblique to the direction of rolling and parallel to a line connecting the corner of the windows with the corresponding outer corner of the core so that substantially all flux in each sheet passes between junctions at opposite ends of each sheet in a continuous straight path along the direction of rolling, the line of junction between said adjoining edges of the sheets of magnetic material of one layer at any corner of the window extending outwardly from an angle point of the sheet offset from the inner angle of the window on one side of and parallel to a line joining the inner corner of the window and the outer corner of the core, and the line of junction between the adjoining edges of any adjacent layer at the same corner extending outwardly from a point offset from the inner corner of the window on the other side of and parallel to the line joining the inner corner of

the window and the outer corner of the core, to provide an overlap of substantially constant width between the adjacent junction lines of said adjacent layers.

2. In an electrical apparatus, a substantially rectangular magnetic core structure built up from layers of sheets of magnetic material formed of steel having preferred magnetic properties in the direction of rolling and so positioned in the structure that the direction of magnetization is substantially coincident with the direction of rolling, each layer comprising a plurality of sheets having adjoining edges adjacent the corners of the core structure and arranged about a substantially rectangular window, the sheets on all sides of the window being of the same width, the junctions of all adjoining edges at the outer corners of the magnetic core extending along lines formed by continuing the inner edge of one of the adjoining sheets at each corner of the window in a straight line in the direction of rolling slightly past the corner of the window to an angle point in the sheet and from that angle point in a continuous straight line at angles oblique to the direction of rolling and parallel to a line connecting the corner of the window with the corresponding outer corner of the core so that substantially all flux in each sheet passes between junctions at opposite ends of each sheet in a continuous straight path along the direction of rolling, the line of junction between said adjoining edges of the sheets of one layer at a pair of alternate corners of the core extending from the inner angles of the window slightly past the corners of the window to the angle points of the sheets in opposite directions from the window in lines parallel to each other, the line of junction between the adjoining edges of said layer at the other pair of alternate corners of the core extending from the inner angles of the window slightly past the corner of the window to the angle points of the sheets in opposite directions from the window in lines parallel to each other and at right angles to the directions of the adjoining edges of the sheets in the same layer at the other two corners of the core, the sheets in any adjacent layer being so arranged that the directions in which the lines of junction extend from the corner of the window to the angle points of the sheets are the reverse of those of the first-named layer, the junction lines in the several adjacent layers from the angle points of the sheets to the outer edge of the core at any one corner of the core extending in parallel directions on the opposite sides of a line joining the corner of the window and the outer corner of the core to provide an overlap of substantially constant width between the junction lines of the adjacent layers.

3. In an electrical apparatus, a magnetic core structure built up from layers of sheets of magnetic material formed of steel having preferred magnetic properties in the direction of rolling and so positioned in the structure that the direction of magnetization is substantially coincident with the direction of rolling, each layer comprising a plurality of sheets arranged to form a substantially rectangular window, the sheets on all sides of the window being of the same width, the junctions of all adjoining edges of any of the sheets in any layer extending along lines formed by continuing the inner edge of one of the adjoining sheets at each corner of the window in a straight line in the direction of rolling slightly past the corner of the window to an angle point in the sheet and from that angle point in con-

tinuous straight lines at angles oblique to the direction of rolling and parallel to a line connecting the corner of the windows with the corresponding outer corner of the core so that substantially all flux in each sheet passes between junctions at opposite ends of each sheet in a continuous straight path along the direction of rolling, the lines of junction between the adjoining edges of the sheets comprising one layer being so arranged that the inner edge of each sheet outlining the window terminates at one end of the sheet at a corner of the window and extends slightly past a corner of the window at the other end to an angle point in the sheet, and from that angle point in a direction parallel to a line from the inner corner of the window to the outer corner of the core, the location of the lines of junction between all adjoining edges being reversed in adjacent layers so that the angle points in the adjacent layers at any corner are on opposite sides of and parallel to a line joining the corner of the window and the outer corner of the core to provide an overlap of substantially constant width between the adjacent lines of junction of the adjacent layers.

4. In an electrical apparatus, a magnetic core structure comprising leg member and yoke members at angles of substantially 90° to each other to form a closed magnetic circuit about a rectangular window, the leg and yoke members being built up of layers of sheet members formed of steel having preferred magnetic properties in the direction of rolling and so positioned in the structure that the direction of magnetization is substantially coincident with the direction of rolling, each layer comprising a plurality of sheets having adjoining edges between leg and yoke members adjacent the corners of the core, the sheets forming the leg and yoke members being of the same width, the sheets in the several layers having their inner and outer lineal edges in alignment and the junctions of all adjoining edges between the sheets at substantially 45° to the lineal edges of the members so that substantially all flux in each sheet passes between junctions at opposite ends of each sheet along a continuous straight path in the direction of rolling, the junctions of all the adjoining edges of said sheet members in a given layer being offset from a line joining the corner of the window and the outer corner of the core, the junctions of the adjoining edges of the sheet members in an adjacent layer at the corresponding corners of the core being on opposite sides of and parallel to the line joining the corner of the window and the corner of the core and parallel thereto to provide an overlap of substantially constant width between the adjacent junction lines of the adjacent layers, the yoke members having the ends adjoining leg members in the same layer offset differently at the opposite ends thereof with respect to the corners of the structure.

5. A magnetic core comprising a plurality of layers of assembled laminations formed lengthwise from strip material having the most favorable magnetic direction lengthwise of the strip, adjacent laminations of layers having substantially mitered butt joints between ends so that a minimum of flux passing from one lamination to another will pass crosswise of the most favorable magnetic direction, said mitered butt joints being displaced from an adjacent diagonal running from the inside corners to the outside corners of the assembled laminations at at least some corners of the assembled laminations, adjacent joints of

contiguous layers at said corners being substantially symmetrically displaced on opposite sides of the adjacent diagonal with a major portion of said joints being parallel to the adjacent diagonals.

6. A magnetic core comprising a plurality of layers of assembled laminations formed lengthwise from strip material having the most favorable magnetic direction lengthwise of the strip, adjacent laminations of each layer having substantially mitered butt joints between ends so that a minimum of flux passing from one lamination to another will flow crosswise of the most favorable magnetic direction, said mitered butt joints of each layer being broken line joints with a major portion of said broken line joint surface being substantially parallel with an adjacent diagonal running from the inside corner to the outside corner of the assembled laminations.

7. A magnetic core comprising a plurality of layers of assembled laminations formed lengthwise from strip material having the most favorable magnetic direction lengthwise of the strip, adjacent laminations of each layer having substantially mitered butt joints between ends so that a minimum of flux passing from one lamination to another will pass crosswise of the most favorable magnetic direction, each of said layers of laminations having broken line joints, a first portion of said broken line joint of one layer being substantially parallel with the longitudinal axis of the assembled core and a corresponding first portion of the adjacent joint of a contiguous layer being substantially parallel with a lateral axis of the assembled core so as to provide overlapping of the adjacent laminations of contiguous layers.

8. A magnetic core comprising a plurality of layers of assembled laminations formed lengthwise from strip material having the most favorable magnetic direction lengthwise of the strip, said layers including at least four laminations assembled with diagonal butt joints at adjacent ends, at least two of said laminations of said layers having edge surfaces in six planes, edge surfaces in four of said planes forming the edges for said butt joints.

9. A magnetic core structure having core members extending at substantially right angles to each other forming an L-shaped corner, said core members each comprising a plurality of sheets of magnetic material having preferred magnetic

properties in the direction of the sheet, the sheets in the adjoining core members adjacent the corner of the core being of the same width and arranged in a like number of layers, the sheets in each of the two adjoining core members of any layer having their adjoining edges in alignment, the junctions between adjacent laminations of each layer of the magnetic material having adjoining edges between their ends extending in a straight line from a point offset from the outer corner of the assembled sheets inwardly in a direction parallel to a line connecting the outer corner of the core structure to the inner corner of the core structure for substantially the entire width of the sheet so that a minimum of flux passing from one lamination to another will pass crosswise of the most favorable magnetic direction, the line of junction between the adjoining edges of the sheets of magnetic material in one layer at the corner of the core extending inwardly from a point offset from the outer corner of the core structure on the other side of the line joining the outer corner of the core structure than does the line of junction between the adjoining edges of the sheets in the adjacent layers.

10. A magnetic core structure having core members forming an L-shaped corner, said core members each comprising a plurality of sheets of magnetic material, the sheets in the adjoining core members adjacent the corner of the core being of the same width and arranged in a like number of layers, the sheets in each of the two adjoining core members of any layer having their adjoining edges in alignment and extending in a straight line from a point offset from the outer corner of the assembled sheets inwardly in a direction parallel to a line connecting the outer corner of the core structure to the inner corner of the core structure for substantially the entire width of the sheet so that a minimum of flux passing from one lamination to another will pass crosswise of the sheet, the line of junction between the adjoining edges of the sheets of magnetic material in one layer at the corner of the core extending inwardly from a point offset from the outer corner of the core structure on the other side of the line joining the outer corner of the core structure than does the line of junction between the adjoining edges of the sheets in the adjacent layers.

ALLAN D. FORBES.
